[57] **CLAIM**

The ornamental design for a container for an oil and waste line connection, as shown and described.

DESCRIPTION

FIG. 1 is a front elevation view of a container for an oil and waste line connection showing my new design;
FIG. 2 is a rear elevation view thereof;
FIG. 3 is a right side elevation view thereof, with a left side elevation view being a mirror image;
FIG. 4 is a top plan view thereof; and,
FIG. 5 is a bottom plan view thereof.
